(57) **CLAIM**

The ornamental design for a computer screen with transitional graphical user interface, as shown and described.

DESCRIPTION

1. Transitional graphical user interface [computer screen layout]

2. Transitional graphical user interface [computer screen layout]

1.1 : A front view of the first image in a sequence of a computer screen with transitional graphical user interface, according to a first embodiment of the new design;

1.2 : A second image thereof;

2.1 : A front view of the first image in a sequence according to a second embodiment of the new design; and

2.2 : A second image thereof.

The appearance of the transitional image sequentially transitions between the images shown in FIGS. 1.1-1.2 and FIGS. 2.1-2.2. The process or period in which one image transitions to another image forms no part of the claimed design.

The broken lines show a computer screen and form no part of the claimed design.
